(57) **CLAIM**

The ornamental design for an illuminated fence post cap, as shown and described.

DESCRIPTION

FIG. 1 is a perspective view of the illuminated fence post cap according to a first embodiment;

FIG. 2 is a top plan view of the cap shown in FIG. 1, the bottom plan view forming no part of the claimed design; FIG. 3 is a front side elevation of the cap shown in FIG. 1, the rear, left and right side elevations being identical thereto; FIG. 4 is a partial sectional view taken through the dome portion of the cap shown in FIG. 3;

FIG. 5 is a perspective view of the illuminated fence post cap according to a second embodiment;

FIG. 6 is a top plan view of the cap shown in FIG. 5, the bottom plan view forming no part of the claimed design;

FIG. 7 is a front side elevation of the cap shown in FIG. 5, the rear, left and right side elevations being identical thereto; FIG. 8 is a perspective view of the illuminated fence post cap according to a third embodiment;

FIG. 9 is a top plan view of the cap shown in FIG. 8, the bottom plan view forming no part of the claimed design; and,

FIG. 10 is a front side elevation of the cap shown in FIG. 8, the rear, left and right side elevations being identical thereto. The broken lines shown in the figures are for the purpose of illustrating the environment, namely the fence post cap adaptor and the fence post, in which the article embodying the design is used and form no part of the claimed design. The partial sectional view in FIG. 4 is provided for the purpose of illustrating the internal surface of the translucent dome not apparent from the others views of the drawings but visible therethrough.
